CONTAINER HOLDER FOR AN AUTOMOBILE

Howard C. Pitts, 100 W. 104th St.,
Kansas City, Mo. 64114

Filed Oct. 11, 1968, Ser. No. 13,941

Term of patent 14 years

Int. Cl. D7—99

U.S. Cl. D44—10

Fig.1.

Fig.2.

Fig.3.

Fig.4.

Fig.5.

FIGURE 1 is a side elevational view of a container holder for an automobile showing my new design, with a tumbler shown in broken lines for illustrative purposes only;

FIG. 2 is a front elevational view;

FIG. 3 is a top plan view;

FIG. 4 is a rear elevational view; and

FIG. 5 is a bottom plan view.

I claim:

The ornamental design for a container holder for an automobile, as shown and described.
